COMBINED CIGARETTE LIGHTER AND
CLOCK

Irving Florman, New York, N. Y.

Application December 29, 1948, Serial No. 150,425

Term of patent 14 years

(Cl. D48—27)

To all whom it may concern:

Be it known that I, Irving Florman, a citizen of the United States, residing at New York, in the county of New York, State of New York, have invented a new, original, and ornamental Design for a Combined Cigarette Lighter and Clock, of which the following is a specification, reference being made to the accompanying drawing, forming a part thereof.

Fig. 1 is a top plan view of a combined cigarette lighter and clock, showing my new design;

Fig. 2 is a front elevational view;

Fig. 3 is a side elevational view of Fig. 2; and Fig. 4 is a bottom view.

The characteristic features of the design are those shown by means of full lines in the drawing.

I claim:

The ornamental design for a combined ciga-

rette lighter and clock, substantially as shown and described.

IRVING FLORMAN.
